TWO-PART HOSPITAL OBSTETRICAL TABLE

Sidney J. Stone, Lyndhurst, Ohio

Application April 5, 1951, Serial No. 219,441

1 Claim. (CL 311—7)

1

This invention relates to improvements in an examination or delivery table and more particularly to a table having a quickly lowerable end portion, or to an auxiliary bed, delivery table or hospital table of very narrow width adapted to be placed alongside or permanently attached to an ordinary hospital bed or at the end of a delivery table.

This application is a continuation-in-part of my co-pending application, Serial No. 755,700, filed June 19, 1947, now U. S. Patent No. 2,610,903, and entitled "Delivery Table."

An object of the present invention is to provide a plurality of patient supporting surfaces, the distal surface of which is quickly lowerable and then returnable to its original patient-supporting position.

Another object of the present invention is to provide a narrow portable bed adapted to be wheeled alongside an ordinary hospital bed after which a woman in labor lying upon a hospital bed may be turned around, her hips placed upon the auxiliary table here disclosed, her legs properly positioned in leg holders, and thereafter the attending obstetrician may deliver the baby thus converting any labor bed into a delivery table.

Another object of the present invention is to connect, preferably detachably, my improved delivery table with a hospital bed so that the delivery table will not move during a delivery operation.

Another object of the present invention is to provide adjustability as to the height of my improved delivery table so that it may support a patient at the right level and at least a portion thereof may be moved downward beneath a woman's hips momentarily to permit the placing of a sterilized sheet beneath her hips, after which the table or the portion thereof is again moved up to hip-supporting position.

Another object of the present invention is to provide a delivery table adapted to be attached to an ordinary hospital bed and having two patient supporting surfaces. One surface being adjustable to the bed level to aid in supporting the patient, and the second or distal surface being quickly lowerable and then returnable to its original patient-supporting position.

By using this table the thighs may easily be lowered to the so-called "Walcher" position—the advantage of which is well recognized by trained obstetricians.

Other objects and advantages of the present invention will be apparent from the accompany-

ing drawings and description, and the essential features thereof will be set forth in the appended claim.

In the drawings,

Fig. 1 is an end elevational view of one embodiment of my invention;

Fig. 2 is a top plan view of the same, with parts broken away to more clearly show the attachment of the delivery table to the hospital bed;

Fig. 3 is a fragmental side elevational view of the same device taken from the right-hand side of Fig. 1;

Fig. 4 is a fragmental sectional view taken along the line 4—4 of Fig. 1, the same being somewhat enlarged;

Fig. 5 is an enlarged fragmental sectional view taken along the line 5—5 of Fig. 1;

Fig. 6 is an enlarged view of a portion of the left side of the frame, as shown in Fig. 1, with parts broken away to more clearly show the construction;

Fig. 7 is an enlarged fragmental view of the mid portion of the right-hand side of the frame, as shown in Fig. 1, with parts broken away to more clearly show the construction;

Fig. 8 is a fragmental side elevational view of a second embodiment of my invention;

Fig. 9 is an end elevational view of the same;

Fig. 10 is an enlarged elevational view, similar to Fig. 9, with parts broken away to more clearly show the construction; while

Fig. 11 is a side elevational view of a third embodiment of my invention.

It is well known that there are difficulties in many hospitals in providing sufficient delivery tables although there are usually sufficient labor beds. The present invention makes it possible to use every bed as a delivery table.

Another disadvantage in present day practice is the difficulty of moving an anesthetized patient from a labor bed onto a delivery table. By the use of my present invention, it is not necessary to move the patient from the labor bed itself but instead her body is manipulated on the labor bed so as to utilize my improved delivery table during the delivery operation. Thus, undesirable movement of the patient is obviated.

Figs. 1 to 7, showing the first embodiment of the invention, disclose a light frame 10 portably mounted upon casters or wheels 11 so that it may be wheeled from place to place. The details of this frame are unimportant except as herein-after specifically referred to. In the drawings 55 four end posts 10a are shown, the two posts at

one end being connected by an upper cross bar 10b and a lower cross bar 10c. Two upper longitudinally extending frame members 10d connect the two upper cross bars 10b. One lower longitudinally extending frame member 10e connects the two bottom end cross bars 10c. These members are all connected together by suitable T-shaped fittings as shown. It will be noted that this provides a strong frame but one which leaves the space clear for the attending physician to stand or sit close to the right-hand edge of the delivery table, as shown in Fig. 1.

The table top consists of a bed portion or patient supporting surface 12. Means is provided for supporting said table top on said frame for vertical movement. This means consists of a quickly operable means for lowering the bed portion and for returning the same to the normal position and an adjustable means for supporting said table in a normal position at a predetermined height.

The first or quickly operable means is provided for lowering and raising the bed portion momentarily to slip a sheet under the woman's hips or for a similar purpose. The drawings show one means suitable for this purpose comprising a toggle 13 although my invention is not limited to this specific means. The bed portion 12 rests upon a structural base 14 to which is rigidly attached a downwardly extending stem 15 which slidably engages within the hollow portion of a pedestal 16 which in turn is rigidly secured to the two frame members 10d. Operating means for the toggle is of a simple type and comprises a link 17 which is connected to a yoke 18, each arm of which has a clevis connection 19 with the mid-point of one element of the toggle 13, there being one yoke arm on each side of the pedestal 16. Rigidly secured to the frame member or upper cross bar 10b is a bracket 20 on which is oscillatably mounted a handle 21 which is pivotally connected to the link 17 at the point or pivotal connection 21a. When the bed portion 12 is in raised or normal position, as shown in Fig. 3, the toggle 13 is slightly over center toward the right and the pin or stop 16a fixed in the pedestal limits further movement of the toggle toward the right. When it is desired to lower the bed, the handle 21 is moved toward the left, as viewed in Fig. 3, permitting the toggle 13 to break toward the left until the bottom of the stem 15 strikes the bottom 16b of the hollow of pedestal 16. Other suitable limiting means may be provided.

The second means comprises the pivot pin 13a of the toggle linkage mounted in any one of a number of suitable openings 13b in the pedestal 16. This adjustable means supports said table top or bed portion 12 in a normal position at a predetermined height approximately on a level with bed 23, as shown in Fig. 1.

Means is disclosed for providing relative vertical adjustment between the top of said table or bed portion 12 and the patient supporting surface or bed 23. This means also connects the delivery table to the bed to prevent separation of them. Any means for attachment to a specific type of bed is within the scope of this invention. As clearly shown in Figs. 1, 2, 3 and 6, the means here provided co-acts with one of the usual longitudinally extending frame members 22 of a common type of hospital bed 23. The bed mattress is shown resting upon this bed frame. Each of the end posts 10a nearest the hospital bed is hollow and receives a screw 24 threaded to receive an adjusting nut 25. The

upper end of the screw 24 is provided with a diametrically extending slot or recess 24a adapted to receive the downturned leg 22a of the angle member 22. With the two screw members 24 in lowered position, the delivery table is wheeled up to the hospital bed with the slots 24a directly beneath downturned leg 22a of the bed frame. The nuts 25 are then manipulated to raise the screws 24 until the downturned leg or frame member 22a firmly engages in the slots or recesses 24a. This holds the delivery table in fixed position relative to the bed. Nuts 25 may be manipulated to cause screws 24 to lift the patient-supporting surface of the mattress of bed 23 to a level corresponding with bed portion 12, if desired.

Leg holders are provided on the delivery or hospital table, if desired. The vertical posts 10a farthest from the hospital bed are hollow and receive vertical adjustment means comprising the adjustable posts 26, each of which is provided with a series of horizontal openings extending clear through the posts as indicated at 26a. The T member 27 is provided with aligned openings 27a through which passes a pin 28 which engages in one of the selected openings 26a so as to hold the post 26 at the desired height. As clearly seen in Figs. 2 and 3, there is one of these posts 26 at each side of the delivery table or bed portion 12. At the top of each of these posts is a leg holder 29. Referring to Figs. 1 and 5, a block 30 is mounted to swivel about each post 26 by means of a thumb screw 31 which engages in an annular groove 32 in the top of post 26. Mounted in each block 30 is an arm 33 having a shank passing through a suitable opening in the block 30 so that the shank of the arm 33 is adjustable in a direction at right angles to the post 26. The end of each arm 33 is provided with a flattened top surface 33a and a thumb screw 34 threaded into the block 30 bears against the surface 33a to hold the arm 33 in various adjusted positions. Each leg holder 29 has a downwardly extending ear 29a which is pivotally mounted on a bracket 35 by means of the horizontally extending pin 36. Each bracket 35 is mounted to swivel about the vertically extending portion 33b of the associated arm 33, by means of a thumb screw 37 which engages in an annular groove 38 at the upper end of the arm portion 33b. This is clearly shown in Fig. 4. Preferably, a vertical adjustment means is provided to permit adjustment of leg holders 29 to hold the knees below the abdomen. This consists of a pin 28 selectively positioned in any one of the openings 26a, as previously described. However, any means for vertical adjustment is within the scope of this invention.

Preferably, the unit is finished by attaching side plates 39 and end plates 40 extending downwardly from the bed base 14 so as to completely enclose the operating parts of the toggle 13. The end plates are slotted as shown at 40a so as to permit the bed portion 12 to be lowered with reference to the frame members 10d.

The second embodiment of the invention is shown in Figs. 8, 9 and 10 wherein the 100 series of the reference numerals used to describe the first embodiment are used wherever possible to designate parts having functions similar to the parts of the first embodiment. Frame 110 is portably mounted upon casters or wheels 111 so that it may be wheeled from place to place. In the drawings, two end frames 110a are shown. Each consists of an upper cross bar 110b and a lower cross bar 110c. Two upper longitudinally extending frame members 110d connect the upper

ends of end frames 110a and two lower longitudinally extending frame members 110e connect the bottom ends of end frames 110a. It will be noted that this provides a strong frame but one which leaves the space clear for the attending physician to stand or sit close to the left-hand edge of the delivery table as shown in Fig. 9.

The table top consists of bed portion or patient-supporting surface 112 and bed surface or patient-supporting surface 123a. Means is provided for supporting said table top on said frame for vertical movement. This means consists of an adjustable means for supporting said table top on a subframe 210 in a normal position at a predetermined height and a quickly operable means for lowering the bed portion and for returning the same to the normal position.

The first means, which moves both bed portion 112 and bed surface 123a, consists of two tubes 115 secured to subframe 210, each slidably mounted on a pedestal 116. A screw 113a is rotatably mounted in a nut 113b attached to each pedestal 116. Each screw 113a is rotatably supported in its tube 115 and is driven by bevel gears 113c and 113d by shaft 113e and handle 113f. When handle 113f is turned, the screw will cause the tubes 115 to telescope over pedestals 116 and to raise or lower table top 112, 123a. The tubes and pedestals are kept in alignment by hanging sleeves 115a mounted on frame members 110d and hanging supports 116b mounted on lower frame members 110e.

The second means, quickly operable for lowering the bed portion 112 of the table top and for returning it to the normal position, is most clearly shown in Fig. 10, at 113.

This means or toggle-like connection 113 consists of a link 117 operatively connected to a lever 118, and its substantially parallel lever 118a, each have one end pivotally connected to bracket 118b, attached to bed portion 112, and each lever has its other end connected to bracket 118c, attached to the subframe 210 of the delivery table. These levers permit the top of bed portion 112 to remain always parallel to the bed surface 123a during its lowering movement. Ample space is provided to slip a sheet under the woman's hips when the bed portion 112 is in its lowest position. Link 117 is driven by handle 121 mounted on shaft 121c through crank arm 121b and pivotal connection 121a. The solid lines in Fig. 10 show bed portion 112 in its raised position while the dot-dash lines show it in its lowered position. Crank arm 121b engages the stop portion 116a of the frame to lock bed portion 112 in its elevated position with toggle-like connection 113 over center.

Means is provided to give relative vertical adjustment between the table top 112, 123a and the patient-supporting surface of said bed 123. This means also connects the table and bed for preventing separation of them. Any means for attachment to a specific type of bed is within the scope of this invention. Bed or patient-supporting surface 123 has a mattress and a longitudinally extending frame member 122. A screw 124, rotatably mounted in post 110a', elevates rod 125a with its slot or recess 124a engaging frame member 122 until bed 123 is approximately level with the normal position of bed surface or patient-supporting surface 123a and bed portion 112. The knob 125b is furnished as a means to drive the screw.

Leg holders are provided at 129, as seen in Fig. 9. A horizontal support 127a extends from post 110a' to support the vertical adjustment

means for each leg holder. This means consists of a threaded, adjustable post 126 mounted in a T member 127. Handle 128b drives a worm gear 128a which in turn drives a worm wheel 128. The worm wheel is internally threaded to co-act with the screw threads 126a on the adjustable post. The slot or key way 126b, engaging a key in T member 127, prevents the adjustable post 126 from turning but permits longitudinal movement thereof. Block 130 is mounted to swivel on top of post 126. Arm 133 has a flattened top surface 133a fitting in a slot in block 130. A flat plate 134a is clamped on the flattened surface by thumb screw 134. The vertically extending portion 133b of arm 133 supports a bracket 135 adapted to swivel on the upper end of said portion 133b. A horizontally extending pin 136 pivotally attaches downwardly extending ear 129a of leg holder 129 to the bracket 135.

The third modification in Fig. 11 is somewhat similar to Figs. 8, 9 and 10. Except that bed portion or patient-supporting surface 112' is permanently attached to bed, bed surface, delivery table, examination table, or patient-supporting surface 123'.

Bed 123' is similar to an examination table, or an ordinary hospital bed or delivery table and is equipped with leg holders 129' and mounted on rollers or wheels 111'. In this modification bed portion 112' is mounted on parallel levers 118' and 118a' exactly like the parts 112, 118, and 118a. Bed portion 112' has all of the adjustments shown in Fig. 10. Handle 121' manipulates a toggle-like connection, similar to 113, connected with levers 118' and 118a' to hold them in raised or lowered position like the full line and dot-dash lines of Fig. 10.

In its broadest aspects, the invention consists of a plurality of patient-supporting surfaces 12, 23, 112, 123, 123a, 112' and 123' of which the distal surface 12, 112 or 112' is quickly lowerable and then returnable to its normal position.

The invention also includes the combining of the two vertical adjustment means for the delivery table top relative to the bed into one single means. For example, screws 24, 124 are disclosed as being part of the means providing relative vertical adjustment between the top of the table or bed portion 12 or 112 and 123a and the body supporting surface of the bed 23 or 123. The pin and opening 13a, 13b and screw 113a are part of the adjustable means for supporting the table top in a normal position at a predetermined height relative to the bed or part of the means for supporting the table top on the frame for vertical movement. All of these means could be defined as or replaced by a single means to perform the functions of relative vertical adjustment of the table and bed, adjustably supporting the table top in a normal position, or supporting the table top on the frame for vertical movement. Each of the above means could interchangeably read on each other or on the aforesaid single means since each performs the same function.

The operation of the device should now be clear. In the first two modifications, the delivery table is moved alongside of the bed and the screws 24 or 124 are manipulated to secure it against movement relative to the bed and to vertically adjust the table top relative to the bed. Of course, in the Fig. 11 modification, this operation is not necessary since the bed portion is attached to the bed. The table top 12, 112, 123a, is ad-

justed to the normal position at proper height by selecting the proper opening 13b or rotating handle 113f. A woman in labor lying upon the bed is moved sideways on the bed by simply sliding her body and without any danger of injuring the mother or the child. The woman's hips are then moved off the bed slightly so that they rest upon the narrow delivery table. I find that a width of the order of six to ten inches is sufficient for the bed portion 12, 112, or 123' because it is desirable that the bulk of the woman's weight should rest upon the hospital mattress of bed 23, 123 or 123'. The length of the bed portion may be anything desired but is usually of the order of several feet. During the preparation of the patient for delivery it is usually desirable to slip a sterilized sheet beneath her hips. The attending physician may do this easily by operating the quickly operable means 13 or 113 to momentarily lower the bed portion at which time the patient's weight rests upon the bed 23, 123 or 123' and bed surface 123a or 123'a' and the support of the legs in the leg holders is sufficient to permit this operation. After this, the bed portion is again raised to the normal position. It will be noted that the leg holders may be freely tilted in any direction about the pivot pins 36, 136 and the lower part of brackets 35, 135. The legs of the patient are usually secured to the leg holder by means of straps passing through the slotted openings 29b, 129b.

It will be noted that the space vertically beneath the edge 12a, for example, is clear in each modification. In other words the frame members are back beneath the bed portion leaving the space clear for the attending physician to stand or sit as close as he desires to the delivery table and permitting the placing of a basin or other receptacle directly beneath the edge 12a of the delivery table. After the baby has been delivered the patient is slid back upon the bed with a minimum of movement, the screws 24, 124 are moved downwardly out of engagement with the bed frame after which the improved delivery table may be rolled away, if desired, in the first and second modifications.

When the patient is in danger of aspirating food or fluids while she is under the anesthetic, the physician may need to use the Trendelenberg position in which the hips are raised slightly higher than the head. Both modifications of this invention, as shown in Figs. 1 to 7 and Figs. 8 to 10, are adapted to make the patient assume this position. Nut 25 in Figs. 1 and 6 or knob 125b in Fig. 9, may raise the bed 23 or 123 respectively, to provide this Trendelenberg position. The above means for positioning table tops 12 and 112, 123a respectively at bed level have been previously described.

What I claim is:

15 A delivery table comprising a frame adapted to be placed alongside a bed, a narrow bed surface supported on said frame portion, a narrow bed portion supported on said frame portion parallel to and adjacent said bed surface, each said bed surface and said bed portion having a length parallel to the side of said bed of the order of a few feet, each said bed surface and said bed portion having a width normal to the side of said bed of the order of six to ten inches, means on said frame for adjusting the top of said bed surface to a normal position level with the top of the body supporting surface of said bed, said bed portion top in normal position being level with the top of said bed surface, and other quickly operable means for lowering the top of said bed portion below, and for returning the same to, said normal position.

SIDNEY J. STONE.
